UNITED STATES PATENT OFFICE.

ANDREW KERR, OF BELFAST, IRELAND.

MEANS FOR CONTROLLING THE SUPPLY OF MOTIVE FLUID TO MARINE ENGINES.

1,091,227.

Specification of Letters Patent. Patented Mar. 24, 1914.

Application filed June 21, 1913. Serial No. 774,959.

To all whom it may concern:

Be it known that I, ANDREW KERR, a subject of the King of Great Britain, residing at Belfast, Ireland, have invented certain new and useful Improved Means for Controlling the Supply of Motive Fluid to Marine Engines, of which the following is a specification.

This invention relates to apparatus for controlling the supply of motive fluid to marine engines and it has for its object to provide control apparatus for anticipating racing and non-racing of the engines when the immersion of the propeller or propellers is decreased or increased by the pitching of the ship or sea falling away from or rising above the propeller or propellers with a consequent decrease or increase of pressure at the stern of the ship.

Under my invention I provide improved apparatus of this class adapted to be operated hydraulically and giving, when required, an automatic complete closing and opening of the throttle or stop valve, and in combination I provide a hand adjusted control arrangement adapted to work at intermediate speeds of the engines whereby the control apparatus may be used when the ship is being driven at intermediate speeds and I also provide in combination with the control apparatus above described the usual hand controlled gear for operating the throttle or stop valve lever. The automatic control is effected through the medium of an anticipating cylinder the piston in which is acted on by the head of water at the ship's stern so that as the pressure head decreases the anticipating cylinder piston falls in its cylinder and as the pressure head increases

the anticipating cylinder piston rises, the movements of the anticipating cylinder piston being adapted to automatically open or close a hydraulic valve to which water is supplied from the main feed pipe and (or) the donkey feed pipe or other suitable source. This automatically controlled hydraulic valve controls the supply of water to a relay valve conveniently situated near the engines which, in turn, is adapted to control the supply of water for operating a piston in a relay cylinder connected directly with a lever for operating the throttle or stop valve and intermediate of the automatic control valve and relay valve I provide conveniently situated cocks or valves by means of which the automatic valve can

be cut out and the relay valve placed under hand control, and I also provide means in connection with the relay cylinder whereby the pressure on its piston may be relieved so that the control of the throttle or stop valve through the relay cylinder may be completely cut out in order that the throttle or stop valve may be operated by direct hand controlled gear. I also provide an air cushioning arrangement to prevent knocking of the relay valve cylinder piston, and I also provide a similar air cushioning arrangement in connection with the relay cylinder piston. I may also, in addition to the automatic anticipating control apparatus provided for a marine engine or engines and in addition to any hand controls provided in connection therewith, provide another supplementary control device which is adapted to control the engine or engines through the medium of the main control apparatus, this additional control device being operated by centrifugal action, inertia and pendulum action.

As the whole of the control apparatus, with the exception of the direct hand gear and, when same is employed, the additional or supplementary control apparatus is hydraulically operated, it is absolutely positive in action and gives automatic control while at sea, hand control at intermediate speeds for use when entering or leaving port or otherwise and it also gives, if desired, the usual direct hand control. The system of cushioning the various pistons is designed to prevent knocking and to make the operation of the apparatus as smooth as possible and so that it will require a minimum of attention.

In order that my invention may be clearly understood I have hereunto appended explanatory sheets of drawings whereon my invention is shown by way of example. The relative positions of the various parts of the apparatus may not of course be as shown in the drawing as they have been simply grouped as shown for convenience in illustrating the invention.

On the drawings:—Figure 1 is a view, mainly diagrammatic, of the main control apparatus. Fig. 2 is a detached view of a cock g showing same arranged to give direct communication between the pipes 3 and 4. Fig. 3 is a detached view of the device for adjusting the sensitiveness of control by the anticipating cylinder. Fig. 4 is a detached

view of a modification of part of the apparatus. Fig. 5 is a side elevation, partly in section, of the supplementary control device. Fig. 6 is an end elevation of the supplementary control device, and Fig. 7 is a plan view thereof, k^o showing the position of lever k when operated by finger g .

On the drawings the same reference letters indicate the same or similar parts.

10 Referring now to Figs. 1-4 of the drawings, a is the anticipating cylinder, b the automatic control valve, c the relay valve and d the relay cylinder, e is the lever controlling the throttle or stop valve, f the main feed water pipe and g the donkey feed water pipe, h is the hand controlled gear for operating the lever e , j is the engine framing and k the ship's skin.

A sea cock l is attached to the ship's skin k 20 at the after end of the tunnel and placed at a suitable depth below the water line, and to this sea cock the anticipating cylinder a is secured. The anticipating cylinder is provided with a plain piston a^1 , to which a piston rod a^2 is suitably secured, and on the piston rod I provide three adjustable tappets t^1 , t^2 , and t^3 . The piston rod a^2 is suitably and slidably supported and secured to a crosshead a^4 to which springs a^5 (see Fig. 3) 25 are attached to give the required degree of sensitiveness of the control by the anticipating cylinder piston a^1 to anticipate and prevent racing, the tension of the springs a^5 being adjustable by means of the screws a^6 , 30 while the adjustment for non-racing is obtained by raising or lowering the lower single pronged tappet t^2 relatively to the double pronged tappet t^1 which should be set between the pawls m^1 , m^2 , (hereinafter described) when the piston a^1 is at the top of the cylinder a . Suitably situated relatively to the piston rod a^2 and adapted to be operated by the tappets thereon are a pair of spring controlled pawls m^1 , m^2 , on a rocking 35 plate m . This rocking plate m is pivoted at m^3 to a fixed support n and at m^4 it is provided with a roller m^5 adapted to bear against a lever o pivoted at o^1 to the support n . This lever o is adapted to act on a 40 roller b^2 on the end of the valve rod b^1 . The valve chest b^0 is conveniently supported on the rods a^7 and it has two ports b^3 and b^4 respectively. The port b^3 is connected by a pipe 1 to a pipe 2 leading to the condenser or hotwell. This pipe 2 is provided with a cock or valve 2^a which controls the speed of the relay piston d^1 . The port b^4 is connected by a pipe 3 with the rear of the piston i^1 in the cylinder i through a valve or cock i^2 and non-return 45 valve i^3 . The piston i^1 is connected directly with the valve c by a rod c^1 so that when the piston i^1 is operated the valve c will also be operated. Water is supplied to the valve c by the pipe 4 leading from an air vessel p 50 to which water is supplied through non-re-

turn valves from the main feed pipe f or the donkey feed pipe g or direct from the boiler through a pipe r and spring loaded valve r^1 , which will prevent water entering from the boiler when under way and water is being obtained from the feed pipes. A branch pipe 4^a from the pipe 4 gives a supply of water to the valve b . The relay valve c has three ports c^2 , c^3 and c^4 . The port c^2 connects by a pipe 5 through a valve or cock d^2 (capable of communicating with the atmosphere) with a port d^3 into the relay cylinder d while the port c^4 communicates by a pipe 6 through valves or cocks d^4 and d^5 (the latter being capable of communicating with atmosphere) with a port d^5 in the relay cylinder d . The port c^3 of the valve c communicates by the pipe 2 with the condenser or hotwell and a cock or valve 2^a is provided in the pipe line 2 and by means of this cock the speed of the relay piston d^1 may be regulated as desired. The ports c^2 and c^4 are preferably provided with valve easing openings c^6 . Intermediate of the valve or cock d^2 and the port d^3 a branch pipe 7 is taken to a port d^6 in the end of the cylinder d , a non-return valve d^7 being provided on the inner face of said port and through the valve or cock d^4 the pipe 6 can be put into communication with a branch pipe 8 which leads to a port d^8 in the other end of the cylinder d , a non-return valve d^9 being provided at the inner face of the port d^8 , and by the cock d^4 the pipe 6 can also be put into communication with one or more intermediate ports d^{10} and the supply to the port d^6 cut off so that the stroke of the piston d^1 may be set at half stroke or other intermediate stroke or full stroke as desired.

When the piston is working only half stroke a stopper d^{11} may be provided to prevent the possibility of the piston d^1 placing the port d^{12} in communication with the port d^7 . Communicating with the end of the relay cylinder d behind the piston d^1 is an air vessel d^{10} and communicating with the other end of the cylinder d is an air vessel d^{11} . The relay cylinder piston d^1 has connected to it a rod d^0 which is adjustably connected with the lever e to which it is pivotally secured at e^1 . d^{13} shows the adjusting means provided on the rod d^0 for adjusting of its length and d^{12} shows a regulating device which may be used to regulate the load on the engine stop valve.

The cylinder i for operating the relay valve c through the medium of automatic control or anticipating valve b or hand-cocks g is also provided with an air vessel i^4 communicating with the rear end of the cylinder i while a non-return air valve i^5 communicates with atmosphere and with the front end of the cylinder i . The cylinder i is also provided with ports i^6 and i^7 , the port i^6 communicating directly with atmosphere and

the port i^7 communicating through the valve or cock i^2 with the pipe 3 and port b^4 of the automatic valve b .

In the pipe lines 3 and 4^a I insert any desired number of cocks or valves q which are normally open as shown in the drawing so as not to interfere with the pipe lines but which can be turned as shown in the detached view Fig. 2, so as to interrupt the pipe line and connect the pipe 3 directly with the pipe 4^a so that at any of such cocks or valves q the relay valve c can be operated independently of the anticipating or automatic valve b . One of the cocks q may, if desired, be connected to an inertia governor actuated from a convenient moving part of the engine so that any excessive acceleration of the engine speed will automatically close the engine stop valve or throttle and keep same shut until opened by the engineer.

A hand lever c^5 with spring catch c^6 is pivoted at c^7 and works over a quadrant c^8 with a slot c^9 therein and the lever is provided with a slot c^{10} engaging a pin c^{11} on the rod c^1 . By means of this lever when the cock i^2 is open to atmosphere, the valve c can be operated by the lever c^5 and the valve moved as desired so that it can be held by the lever c^5 in mid position by causing the spring catch c^6 to engage the slot c^9 . When this has been done the relay piston can be held at any desired position to give any desired opening of the stop valve.

I will now describe the operation of the apparatus hereinbefore described under different conditions.

The tappets t^2 and t^3 are first adjusted so that the tappet t^2 will act under any usual pitching of the ship, the tappet t^3 being set for use in very heavy weather when there is rapid pitching and the propeller or propellers is or are lifted right out of the water. The two tappets are identical in their action but the one comes into operation before the other. The springs a^5 are then adjusted so that their downward pull on the piston a^1 is greater than the pressure of the head of water at which acceleration or racing of the propeller or propellers would take place so that before the propeller or propellers can rise sufficiently to cause racing of the engines the piston a^1 descends and the lowest tappet t^1 engages the pawl m^2 and thereby oscillating the rocking plate m and causing the roller m^5 to push back the lever o taking with it the rod b^1 and so operating the valve b and passing a supply of water therefrom through the port b^4 into the pipe 3 through the valve or cock i^2 and non-return valve i^3 to the rear of the piston i^1 causing same to be pushed forward in its cylinder and thereby operating the valve c causing it to close the port c^2 and to open the port c^4 to a supply of water which then passes through the

port c^4 into the pipe 6, through valves or cocks d^4 and d^{14} , branch pipe 8, non-return valve d^9 to the rear of the piston d^1 and forcing same forward and thereby moving the rod d^0 and lever e and causing the latter to close the stop valve and shut off steam from the engines until, by the lowering or falling of the stern the pressure head on the piston a^1 causes it to act in the reverse direction then the tappet t^3 , t^2 or t^1 engages the pawl m^1 and reverses the action of the rocking plate m and valve b , causing the latter to close the port b^4 to the supply of water and opening it to the port b^3 , pipe 1 and condenser pipe 2. This position of the valve b is shown in the drawings. This reverse action of the tappets, rocking plate m and valve b anticipates non-racing and due to the opening of the port b^4 to the condenser, the pressure is withdrawn from the rear of the piston i and the area of the valve spindle c^1 is such that when this takes place, the pressure of water thereon forces the piston i^1 back to the position shown in the drawings. At this position of the valve c water is admitted through the port c^2 to the pipe 5 and from thence through the port d^6 or d^3 and so forcing back the piston d^1 in the relay cylinder d to the position shown in the drawings, at which position the stop valve will have been opened to admit steam to the engines. Of course if the relay cylinder d is only being worked at half or other intermediate stroke then the travel of the piston d^1 would be correspondingly less.

When it is desired to operate the stop valve lever e by means of the apparatus but independently of the anticipating gear, then, by turning any of the cocks or valves q to the position shown in Fig. 2, the supply of water from the pipe 4^a will be intercepted and passed directly into the cylinder i to operate the piston therein and so effect the movement of the relay valve and relay piston as hereinbefore described to close the stop valve.

When it is desired to operate the stop valve lever e by means of the direct hand gear h the rod h^1 which is shown in the drawings free to slide up and down as the lever e is operated by the relay piston, is secured in the socket h^2 of the rod h by means of a cotter h^3 shown in its working position in dotted lines and passing through a slot in the lower end of the rod h . The cocks d^2 and d^{14} are then opened to atmosphere so that the pressure on either side of the piston d^1 is entirely relieved and the hand gear h can then be freely operated to open and close the stop valve as required.

In order to prevent knocking of the piston i^1 I provide an air cushioning arrangement. This consists in providing the port i^6 , non-return air valve i^5 and air vessel i^4 so that as the piston moves forward it traps air at its

front end and as it moves backward the water at the rear of the piston rises in the air vessel d^4 cushioning against the air at present at the top of same. Similarly 5 air vessels d^{10} and d^{11} prevent knocking of the piston d^1 .

In order to facilitate the operation of the valve c I provide the easing openings c^0 at 10 each side of the ports c^2 and c^4 so that as the valve is moved to open said ports there would be a preliminary opening of the ports to the easing openings c^0 .

It will be seen that the entire apparatus 15 is designed to meet the requirements under practically all conditions at sea or when entering or leaving port and that provision is also made whereby the apparatus may be used even if the main feed and donkey feed are off by obtaining a supply of water from 20 the boilers.

In order to nullify the effect of leakage of the valve b through the port b^4 and to prevent the possibility of the piston i being in this way accidentally operated I preferably 25 provide a third port to the valve chest b^0 as shown at Fig. 4 and I preferably make the connections between the valve b and cylinder i as shown in Fig. 4. In this case the port b^4 by the pipe 3 connects through the cock q^1 , cock i^2 and non-return valve i^3 with the 30 rear of the cylinder i . The port b^3 communicates by the pipe 1 with the condenser pipe 2 and the port b^5 connects by a pipe 8 through the cock q^1 , pipe 8^a , cock i^8 (capable 35 of communicating with atmosphere) and non-return valve i^9 to the front of the cylinder i . The cock q^1 is in communication with the feed pipe 4^a which leads to the valve chest b^0 . The arrangement is such 40 that with the valve b closing the port b^4 to supply as shown and open to condenser the condition will be exactly as hereinbefore described with reference to Fig. 1 but, water will be supplied through the port b^5 , pipe 8, 45 cock q^1 , cock i^8 , non-return valve i^9 , to the front of the piston i^1 , thereby holding same over so that any leakage at the valve b will not interfere with the working of the apparatus. With this arrangement when it is 50 desired to operate the piston i^1 through the medium of the cocks q^1 then any of said cocks will be turned until the port q^2 communicates with pipe 3^a and the port q^3 communicates with the pipe 8^a in which position 55 the port q^3 will also be in communication with the pipe 3 and through the ports b^4 and b^3 with the condenser or hotwell. The port q^4 will in this position of the cock q^1 be in communication with the water feed pipe 4^a and through the port q^2 will give a supply 60 of water through the pipe 3^a , cock i^2 , non-return valve i^3 to the rear of the cylinder i .

Referring now to Figs. 5-7 of the draw-

ings the supplementary control device 65 comprises a slidably supported weight u , the slide v which supports the weight being pivotally supported at one end v^1 and adapted to be oscillated on its pivotal supports, its oscillation being obtained in any suitable 70 and convenient manner from a moving part or parts of the engine or engines, for instance it may be rotated or oscillated from or by the "counter" of the engine. The 75 slidable weight u is connected by spring or equivalent means w with the inner or pivotally supported end v^1 of the oscillating slide v and it is provided with projections or fingers x, y , capable of engaging levers z , 10, adapted to control the opening and closing of a cock or valve 11 or an electric switch adjustably supported in the framing 12, said cock or valve 11 or switch being the same as or the equivalent of the cock q inserted in the pipe lines 3 and 4^a of the 80 main control apparatus hereinbefore described. The cock or valve 11 is normally maintained open by the device but when the normal speed of the engine or engines is exceeded then the corresponding increase 85 in the rate of oscillation of the slide v which supports the weight or sliding member u will cause the latter under centrifugal action to move outward along the slide v thereby causing the projecting finger or 90 member x which is adapted to open the cock or valve 11 and which normally keeps the cock 11 open with the pipe lines 3 and 4^a uninterrupted, to be moved clear of its corresponding cock controlling lever z and at 95 the same time such a movement of the weight u will cause the other projecting finger or member y when a predetermined excessive speed of oscillation has been attained 100 to engage with its corresponding cock or valve controlling lever 10 causing it to turn the cock or valve 11 so that it connects the pipe line 3 with the pipe line 4^a , whereby the relay valve c is operated in the manner and with the result hereinbefore described, 105 and the slidable weight due to the inertia which has to be overcome before it can be caused to move also allows normal variations in speed to take place without affecting 110 the control cock q .

The sensitiveness of the apparatus is increased during periods when the ship is pitching with a head sea with a resultant anticipating action of the control device. This is caused by the weight or slide u tending 120 to move outward when the bow of the ship dips and causing the supporting slide to take a correspondingly inclined position when the weight u will tend to slide downward on same and so assist or anticipate the 125 movement which causes the finger y to engage and move the lever 10 and so move the valve or cock 11 and cause it to connect the 115 120 125

pipe line 3 with the pipe line 4^a, with the reverse action when the bow is rising. With a following sea the device would be turned on its pivot 13 and the operating connection correspondingly changed so that the anticipating action would take place when the stern is dipping. The reverse of this action will take place when the bow is dipping.

10 In order to prevent accident and damage to the engines when from any cause they start racing at a very excessive speed such as might happen if the propeller was carried away, I provide a catch 14 under the 15 action of a spring 15 or equivalent and a corresponding projection 16 on the weight *u* so adapted that the projection 16 can slide freely over the catch 14 in one direction but when once it has moved beyond the catch 20 14 it cannot move back until the catch 14 has been moved clear by the engineer. Under this arrangement when the projection 16 is caught by the catch 14 the steam or other supply is completely cut off and the engines 25 thereby stopped until the engineer has repaired the damage and has decided that the engines can be again set in motion.

I preferably provide ball or roller bearings at 17 to make the action of the weight 30 *u* as free from friction as possible. The connection at the pipes 3 and 4^a to the cock or valve 11 would be flexible to permit of the necessary movements.

The whole control apparatus or device is 35 pivotally supported at 13 and it is capable of being turned to suit for going ahead or astern as described, a connection 18 or equivalent being provided at each side of the slide *v* for connecting same to the 40 counter or other moving part of the engine or engines. If desired the oscillation of the slide *v* may be obtained by a pull on one side only the return action being effected by a spring or springs 19 as shown in dotted 45 lines Fig. 5. Provision is also made by means of the securing holes 20, 21, in the bracket 22 whereby the device can be used to operate by a beam sea either to port or to starboard. This is provided more particularly for twin screw steamers. The connection or connections to the ring 18 would 50 of course be arranged to suit.

Having now fully described my invention what I claim and desire to secure by Letters Patent is:—

1. In a device of the character stated, the combination, with a supply of fluid under pressure, of a stop valve controlling lever, a cylinder, a piston therein connected with 55 said controlling lever, a valve controlling the supply of pressure fluid to said cylinder, a second cylinder, a piston therein connected to said valve, a second valve controlling the supply of pressure fluid to said second cyl-

inder, means whereby said second valve is 65 normally maintained at such a position that fluid under pressure is cut off from said second cylinder, a pipe leading from a supply port of said second valve to the supply port into said second cylinder, a pipe leading 70 from a second supply port of said second valve direct to the casing of the first valve, a cock interposed in said pipe lines and normally leaving them connecting the valves and cylinder as above stated but having 75 ports therein capable of being turned so as to place the two pipe lines in communication with each other and cutting off the connection with the second valve and placing the pressure fluid in direct communication 80 with said second cylinder and without passing through said second valve.

2. In a device of the character stated, the combination, with a supply of fluid under pressure, of a stop valve controlling lever, a 85 cylinder, a piston therein connected with said controlling lever, a valve controlling the supply of pressure fluid to said cylinder, a second cylinder, a piston therein connected to said valve, and a cock for controlling the 90 supply of fluid under pressure to said second cylinder.

3. In a device of the character stated, the combination, with a supply of fluid under pressure, of a stop valve controlling lever, a 95 cylinder, a piston therein connected with said controlling lever, a valve controlling the supply of pressure fluid to said cylinder, a second cylinder, a piston therein connected to said valve and means whereby fluid 100 under pressure is admitted to said second cylinder when the speed of the engine exceeds a predetermined limit.

4. In a device of the character stated, the combination, with a supply of fluid under 105 pressure, of a stop valve controlling lever, a cylinder, a piston therein connected with said controlling lever, a valve controlling the supply of pressure fluid to said cylinder, a second cylinder, a piston therein connected to said valve, a cock for controlling the 110 supply of fluid under pressure to said second cylinder and means whereby said cock is opened to connect the fluid supply to said second cylinder when the speed of 115 the engine exceeds a predetermined limit.

5. In a device of the character stated, the combination, with a supply of fluid under pressure, of a stop valve controlling lever, a 120 cylinder, a piston therein connected with said controlling lever, a valve controlling the supply of pressure fluid to said cylinder, a second cylinder, a piston therein connected to said valve, a cock for controlling the supply of fluid under pressure to said second 125 cylinder, a slide pivotally mounted and adapted to be oscillated by the engine, a weight suspended in said slide and means

- whereby when the engine exceeds a predetermined speed the outward movement of the weight due to centrifugal action opens said cock to admit fluid under pressure to 5 said second cylinder.
6. In a device of the character stated, the combination, with a supply of fluid under pressure, of a stop valve controlling lever, a cylinder, a piston therein connected with 10 said controlling lever, a valve controlling the supply of pressure fluid to said cylinder, a second cylinder, a piston therein connected to said valve, a cock for controlling the supply of fluid pressure to said second cylinder, a controlling lever thereon, a slide pivotally mounted and adapted to be oscillated by the engine, a weight suspended in said slide and a projecting finger thereon adapted to engage said cock controlling lever and open 15 the cock to admit fluid under pressure to said second cylinder when the engine exceeds a predetermined speed.
7. In a device of the character stated, the combination, with a supply of fluid under 20 pressure, of a stop valve controlling lever, a cylinder, a piston therein connected with said controlling lever, a valve controlling the supply of pressure fluid to said cylinder, a second cylinder, a piston therein connected to said valve, a cock for controlling the supply of fluid pressure to said second cylinder, a controlling lever thereon, a second controlling lever thereon, a slide pivotally mounted and adapted to be oscillated by the engine, a weight suspended in said slide and a projecting finger thereon adapted to engage said first mentioned cock controlling lever and cause it to open the cock to admit fluid under 25 pressure to said second cylinder when the engine exceeds a predetermined speed and to engage said second lever which is adapted to close the cock and so release the pressure at piston in said second cylinder and open 30
- 40

the stop valve when normal speed is again attained.

8. In a device of the character stated, the combination, with a supply of fluid under pressure, of a stop valve controlling lever, a cylinder, a piston therein connected with said controlling lever, a valve controlling the supply of pressure fluid to said cylinder, a second cylinder, a piston therein connected to said valve, a cock for controlling the supply of fluid under pressure to said second cylinder, a controlling lever thereon, a slide pivotally mounted and adapted to be oscillated by the engine, a weight suspended on springs in said slide and a projecting finger thereon adapted to engage said cock controlling lever and open the cock to admit fluid under pressure to said second cylinder when the engine exceeds a predetermined speed and the centrifugal force exerted upon the weight overcomes the suspending springs.

45

9. In a device of the character stated, the combination, with a supply of fluid under pressure, of a stop valve controlling lever, a cylinder, a piston therein connected with said controlling lever, a valve controlling the supply of pressure fluid to said cylinder, a second cylinder, a piston therein connected to said valve, a cock for controlling the supply of fluid under pressure to said second cylinder and means whereby when the speed of the engine becomes excessive said cock is opened to connect the fluid supply to said second cylinder and maintained open until manually adjusted.

60

In testimony whereof I affix my signature in presence of two witnesses.
